DES. 2192

Francis J. Pierce, of Roxbury, Mass.

Assignor to

The Roxbury Carpet Company of the same place.

Letter Patent No. 2192 Dated Oct 10-1865

Design for a Carpet Pattern.

The schedule referred to in these Letters Patent and making part of the same.

To all Persons to whom these Presents shall come:

Be it known that Francis J. Pierce, of Roxbury, in the County of Norfolk and State of Massachusetts, have invented a new ornamental design for a carpet or other fabric or manufacture, and I do hereby declare the same to be fully represented in the accompanying drawing.

The said drawing consists of a lozenge-shaped shield, having a roseb. in each corner. These roses are connected by shadow wreaths c. of leaves, and encompass a bouquet d. or bunch of flowers. There is a curved and leaved stalk e. on each side of the lozenge. The ground of the figure both above and below the lozenge is ornamented with leaves, flowers and fruits in manner as indicated in the drawing.

What I claim as my invention is, The ornamental design as herein set forth and as represented in the accompanying drawing, and intended for carpets or other fabrics.
